CIRCUIT BREAKER

Fritz Rampacher, Berlin-Charlottenburg, Germany, assignor to Westinghouse Electric & Manufacturing Company, a corporation of Pennsylvania

Application November 6, 1928, Serial No. 317,588
In Germany November 9, 1927

11 Claims. (Cl. 200—89)

My invention relates to circuit breakers and particularly to circuit breakers of the oil-immersed type wherein the contacts are immersed in oil.

- 5 An object of my invention is to provide a circuit breaker wherein the movable contacts may be moved to open position at a relatively high velocity in order to reduce the arcing incident to separation of the contacts.
- 10 Another object of my invention is to provide a circuit breaker wherein the movable contacts are mounted upon the movable carrier therefor in such manner that, upon the occurrence of a severe overload or short-circuit, the movable contacts are caused to move to open position independently of any movement of the carrier, thereby making it unnecessary to overcome the inertia of the carrier when the circuit breaker is opened under overload and short-circuit conditions.
- 15 A further object of my invention is to provide a circuit breaker having the above noted characteristics wherein the carrier for the movable contacts is moved away from and toward the fixed contacts under normal operating conditions to move the bridging contacts of the circuit breaker out of and into operative engagement with the fixed contacts.
- 20 A further object of my invention is to provide a circuit breaker having movable contacts mounted on a carrier in such manner that they may move, independently of the carrier, to open position with a snap action when an overload or short-circuit condition occurs and wherein means are provided for resetting the movable contacts and wherein the operating mechanism for the re-setting means and the carrier are interlocked in such manner that a predetermined sequence of operation thereof is necessitated.
- 25 Further objects that will be made apparent throughout the further description of my invention are attained by means of the apparatus hereinafter described and illustrated in the accompanying drawing wherein:
- 30 Figure 1 is a vertical sectional view of a circuit breaker embodying features of my invention;
- 35 Fig. 2 is an elevational view of the circuit breaker carrier and re-setting mechanism, and
- 40 Fig. 3 is an elevational view of a modified form of circuit-breaker-operating mechanism.

Referring to the drawing, the circuit breaker comprises a metal tank or container 4 supported by a cover 5 from which the tank may be detached for the purpose of attaining access to

the circuit-breaker apparatus mounted upon the cover, the tank being normally filled with an insulating, arc-extinguishing liquid, such as oil or substances having similar characteristics. Two insulating bushings 6, that are mounted in 5 the cover 5, serve to support the fixed contacts 7 of the circuit breaker which comprise flexible jaws 8 that are adapted to yieldingly engage movable contacts 9 that are movably mounted upon a cross bar or carrier 11, in a manner to be 10 hereinafter described.

The cross bar 11 is adapted to slide vertically upon the guide bars 12 that are secured to the cover 5 and is operated by a pair of connecting rods 13 that are moved vertically through the 15 medium of a cam 14 (Fig. 2) that is fixed to, and rotates with, an operating shaft 15.

The bar or carrier 11 is made of insulating material and supports two metal cylinders 16 which serve to support and guide the movable contacts 9, the lower ends of which are provided with flat heads 17 that are engaged by helical springs 18 which surround the contact 9 and are confined within the cylinders 16, as indicated in Fig. 1. The contacts 9 are adapted to be moved to the open position, indicated in dotted lines in Fig. 1, by the springs 18 one of which is shown. The contacts 9 are releasably retained in their closed positions, shown in full lines in Fig. 1, by means of the latches 19 comprising bell-crank levers that are pivoted at 21 upon the cylinders 16 and are provided with horizontally extending limbs 22 upon which a flexible connector 23 of U-shape is supported at its central portion, the ends of the connector being conductively connected to the cylinders 16 by conductive brackets 24.

In order to maintain conductive contact between the contacts 9 and the brackets 24, contact shoes 25 are provided for engaging the flat head 17 of the contacts 9, regardless of their positions in the cylinders 16, the shoes being yieldingly held in engagement with the flat head 17 by leaf springs 26 connected to the brackets 24. The brackets 24 also carry leaf springs 30 which serve to yieldingly retain the latches 19 in engagement with the flat head 17 of the contacts 9.

When a severe overload or short-circuit occurs in the circuit in which the circuit breaker is connected, the abnormal current flow will cause displacement of the central portion of the flexible connector 23 downward, thereby depressing the limbs 22 of the latches 19 and causing the latches 19 to release the contacts 9 and permit the springs

18 to move them to open position with a snap action and at a relatively high velocity. It will be readily understood that, since the contacts 9 are relatively light, much less effort is necessary 5 to move them at a high velocity than would be required to overcome the inertia of the entire carrier and its associated parts and move it to open position. The actuating mechanism for operating the circuit breaker contacts under over- 10 load and short-circuit conditions is, therefore, of a lighter character and less expensive and cumbersome than the apparatus usually required to open a circuit breaker of the usual type wherein the entire carrier is moved to open the circuit 15 breaker. Furthermore, relatively high velocities of separation of the contacts are obtainable by reason of the construction above described.

It will be understood that, during ordinary normal operation of the circuit breaker, the carrier 11 is moved vertically to separate the contacts 9 from the contact jaws 8, and that the contacts 9 are moved relative to the carrier only in response to overload and short-circuit conditions.

In order to reclose the circuit breaker after it 25 has been opened, under overload or short-circuit conditions, and to insure that a definite time interval transpires before the circuit breaker is again closed, provision is made for necessitating opening movement of the carrier 11 before the 30 circuit breaker contacts 9 can be reset to operative position.

I have, therefore, provided a resetting bar 21 that is mounted upon the guides 12 for vertical movement and carries two resetting pins 28 axially aligned with the contacts 9 for moving them to reset position after the bar 11 has been moved to its lowermost position, indicated in dotted lines in Fig. 1.

As indicated in Fig. 2, the bar 11 is actuated by 40 means of a cam 14 having an arcuate face 20, and the bar 21 is actuated by means of rods 29 that are operated by a cam 31 having a concave arcuate face 32. The cams are, therefore, interlocked in such manner that a predetermined sequence of operation thereof is required.

In order that the resetting bar 21 may be raised to reset the circuit-breaker contacts 9, the cam 14 must be moved to the open position, indicated in dotted lines in Fig. 2, thus causing 50 the bar 11 to be moved to its lowermost position. After this movement has been completed, the cam 31 may be rotated by a shaft 33 in a clockwise direction to cause upward movement of the resetting bar 21. It will be seen that the cam 14 55 cannot be returned to its original closed position until the resetting bar 21 has been returned to its original lowermost position.

By reason of the interlock operating mechanism, in order to reset the circuit breaker after 60 operation in response to an overload or short circuit, the carrier 11 must first be lowered, the resetting bar 21 then raised to reset the contact 9 and returned to its original position and then the carrier 11 may be raised to bring the contacts 9 into operative engagement with the contact jaws 8.

In Fig. 3, I have disclosed a modified form of 70 circuit-breaker-contact-operating mechanism that also accomplishes initial movement of the contacts without necessitating substantial movement of the movable contact carrier. In this construction, the fixed contact members 7 are provided with movable contact members 34 in the 75 form of bell-crank levers that are pivoted at 35 upon the contact members 7 and are provided

with vertical limbs 36 that are releasably retained in operative position by latches 37 comprising bell-crank levers 38 that are normally biased toward latching position by springs 39. Movable pawls 41 are pivotally mounted on the 5 ends of the lever 38 and are engaged by a releasing bar 42 that is secured to the operating shaft which carries the movable contacts 44 of the circuit breaker which are mounted on a cross bar 45 secured to the shaft 43.

10 Springs 46, which engage heels 47 on the contact members 34, serve to bias the contact members 34 toward open position and to rotate the contact members in opposite directions away from the contacts 44 when the latches 37 have released 15 the limbs 36.

The operating shaft 43 is adapted to be released by the ordinary circuit-breaker trip mechanism in response to a severe overload or short circuit. The initial downward movement of the 20 shaft 43 causes the latches 37 to be released from the limbs 36 of the contacts 34, which permits their opening movement by the springs 46, with a snap action.

It will thus be seen that the contacts separate 25 at a relatively high velocity upon a slight initial movement of the carrier for the movable contacts 34. The subsequent downward movement of the cross bar 42 serves to return the contacts 34 to their original positions, ready for the next operation.

When reclosing the circuit breaker, the shaft 43 is raised, bringing the contacts 44 into engagement with the contacts 34. The ends of the releasing bar 42 slip past the pawls 41 and re-engage them. The parts of the apparatus will 35 then occupy their original positions, as indicated in Fig. 3.

While I have illustrated only two embodiments 40 of my invention, it will be apparent to those skilled in the art that various changes, modifications, substitutions, additions and omissions may be made in the apparatus illustrated without departing from the spirit and scope of my invention, as set forth in the appended claims.

45 I claim as my invention:

1. The combination with a pair of relatively 50 movable contacts, of a movable carrier for one of the contacts having operating means movable to two operating positions, means for movably supporting the said contact upon the carrier for disengaging movement independently thereof, current-responsive means for releasably retaining the said contact in engagement with the other contact when the operating means for the carrier 55 is in one of its operating positions, and means movable for resetting the said contact that is operable only when the operating means for the carrier is in its other operating position.

2. The combination with a pair of relatively 60 movable contacts, of a movable carrier for one of the contacts movable to two operating positions, means for movably supporting the said contact upon the carrier for disengaging movement independently thereof, current-responsive means 65 mounted on the carrier for releasably retaining the said contact in engagement with the other contact when the carrier is in one of its operating positions, and means movable for resetting the said contact that is operable only when the carrier 70 is in its other operating position.

3. A circuit breaker comprising a fixed contact, a movable contact for engaging the fixed contact, a movable member having a latch portion for supporting the movable contact and for permitting 75

relative movement of the movable contact with respect thereto, means for moving the movable contact to open position independently of movement of the bar, and current-responsive means mounted to move only with said movable members for releasably retaining the movable contact in operative engagement with the fixed contact.

4. A circuit breaker comprising a pair of fixed contacts, a pair of movable contacts for engaging the fixed contacts, a bar movable between open and closed circuit positions for supporting the contacts and for permitting relative movement of the movable contacts with respect thereto, means for moving the movable contacts to open position independently of movement of the bar, current-responsive means for releasably retaining the movable contact in operative engagement with the fixed contacts, and means movable only when said bar is in open circuit position for resetting the movable contacts.

5. A circuit breaker comprising a pair of fixed contacts, a pair of movable contacts for engaging the fixed contacts, a movable bar for supporting the contacts and for permitting relative movement of the movable contacts with respect thereto, means for moving the movable contacts to open position independently of movement of the bar, current-responsive means for releasably retaining the movable contacts in operative engagement with the fixed contacts, means for resetting the movable contacts, and interlocked operating means for the bar and the resetting means, whereby a predetermined sequence of operation thereof is required.

35 6. An automatic circuit breaker comprising in combination, a movable contact member biased toward its open-circuit position, a movable actuating member normally adapted to move the contact member to open or close the circuit, and an electro-responsive means inherently responsive to abnormal current conditions in the circuit carried by said actuating member and constituting at least a part of a mechanical connection between the said actuating and contact members normally operative to prevent independent circuit opening movement of the latter, the said means upon the attainment of an abnormal current condition in the circuit being relatively movable by

reason of its own inherent electro-responsive characteristics so as to render the said mechanical connection ineffective and to thereby permit the contact member to move to its open-circuit position independently of the actuating member. 5

7. An automatic circuit breaker as set forth in claim 6, wherein the electro-responsively movable means includes a latch carried by one of the said members and normally having a direct engagement with the other, the said latch being automatically disengaged from the said other member upon the attainment of an abnormal circuit condition so as to permit independent movement of the contact member. 10

8. An automatic circuit breaker as set forth in claim 6, wherein the entire electro-responsive means is bodily movable with the said actuating and contact members during normal opening and closing of the circuit breaker. 15

9. An automatic circuit breaker as set forth in claim 6, wherein there are two separate circuit breaking contacts on the contact member and wherein the entire electro-responsive means is bodily movable with the actuating member and is electrically connected between the said contacts. 20 25

10. An automatic circuit breaker as set forth in claim 6, wherein the actuating and contact members are normally movable in fixed relationship with each other and wherein the entire electro-responsive means is bodily movable with the said contact member only during normal opening and closing of the contact member. 30

11. An electric circuit breaker comprising a pair of fixed contacts and a conducting switch member including a pair of movable contacts, an operating rod for moving said movable contacts into and out of engagement with said fixed contacts, said operating rod being relatively movable with respect to said movable contacts, means biasing said movable contacts to move towards open circuit position independently of said rod along the same line as when moved by said rod, and electromagnetic tripping means holding said switch member in closed circuit position, said conducting switch member comprising the current-carrying element of said tripping means. 35 40 45
